UNITED STATES PATENT OFFICE.

THOMAS B. PODBURY, OF HYDE PARK, MASSACHUSETTS.

DESIGN FOR A HANDKERCHIEF.

SPECIFICATION forming part of Design No. 23,798, dated November 13, 1894.

Application filed March 30, 1894. Serial No. 505,775. Term of patent 3½ years.

To all whom it may concern:

Be it known that I, THOMAS B. PODBURY, a citizen of the United States, residing at Hyde Park, in the county of Norfolk, Commonwealth of Massachusetts, have invented and produced a new and original Design for Handkerchiefs, of which the following is a specification, reference being had to the accompanying drawing, illustrating the same.

The leading feature of my design for handkerchiefs consists in the representation *a* of a plurality of playing cards, upon a suitable background *b*, the cards being suitably arranged and grouped as shown to present a substantially rectangular border with an inclosed

central figure. The corners and ends of the cards overlap one another, as shown, to give a more free and careless appearance to the disposition of the cards in the design.

I claim—

The design for handkerchiefs and the like herein shown and described.

In testimony whereof I have signed my name to this specification in the presence of two subscribing witnesses.

THOMAS B. PODBURY.
